UNITED STATES PATENT OFFICE

1,963,620

HONING APPARATUS

Joseph H. Gettig and Allen D. Gettig, Ellwood
City, Pa., assignors to National Tube Company,
a corporation of New Jersey

Application December 27, 1932, Serial No. 649,072

3 Claims. (Cl. 51—191)

This invention relates to improvements in honing apparatus, and more particularly to apparatus for honing the interior of tubular work-pieces.

- 5 One object of the invention is the provision of novel apparatus for completely and thoroughly grinding or polishing the entire length of the interior of tubular work-pieces in a single operation.
- 10 Another object is to provide a novel internal and radially expanding rotary hone which, due to its flexibility, will make complete contact with the entire interior surface of a tubular work-piece that may not be perfectly straight.
- 15 A further object of the invention is the provision of a novel work-piece carriage and associated mechanism for reciprocating the same.

These and further objects will appear after referring to the drawings, in which:

- 20 Figure 1 is a side elevation of the apparatus of the invention, showing the work-piece partly in section.

Figure 2 is a plan view of the apparatus of Figure 1.

- 25 Figure 3 is an end view taken along the line III—III of Figure 1.

Figures 4, 5, 6, 7, 8, 9 and 10 are detail views of the improved hone of the invention.

Referring more particularly to the drawings, the numeral 2 indicates a web and 3 the flanges forming the bed for the machine of the invention. A spindle housing 5 is mounted on a support 4 which is secured to the spindle and has rotatively associated therewith a spindle 6. The spindle 6 is provided at one of its ends with a pulley 7 and at the other end with a coupling 6^c. The pulley 7 receives movement from a belt 8 which is driven from a larger pulley 9 which is, in turn, driven by a motor 10 supported upon a motor bed 11.

- 40 The work-piece carriage of the invention comprises a pair of vertical supports 12, provided with wheels 13, which are arranged for longitudinal movement on the flanges 3 of the bed. The supports 12 are provided with clamping segments 14 and a wheel 15 for clamping a tubular work-piece 18 therebetween. The supports 12 are attached in spaced relationship by a pair of tubes 16 having internal rods 17 extending through the vertical supports 12 and provided at their ends with threads for the nuts 17^a. The carriage formed by the vertical supports 12 is provided at each of its ends with a block 19 having grooved portions 19^a and a cooperating block 20 having similarly grooved portions 20^a. The block 20 is provided 50 with a bolt 21 which extends through the block 19

and on which there is provided a hand-wheel 22 for clamping reciprocating rods 23. The rods 23 are journaled in suitable bearings 4^a in the spindle housing support 4 and are provided at one of their ends with a coupling 23^a.

60 A drive gear housing 24 is positioned adjacent the spindle housing support 4 and is provided with a shaft 25 and disks 26 having offset pins 27. Connecting rods 28 are secured to the pins 27 on the disks 26 and to the couplings 23^a by means of pins 23^b. Rotative movement is given the shaft 25 by means of a motor 28^a and associated power coupling mechanism 29.

65 Referring to Figures 4, 5, 6, 7, 8, 9 and 10, there is disclosed an improved centrifugally actuated expanding internal rotary hone which comprises a tubular portion A provided with a hole 6^b for accommodating a rod 6^a which is secured to the rotary spindle 6 by means of the coupling 6^c. The tube A is provided with radially disposed longitudinal flanges B which extend beyond the ends of the tube A and which are made integral with the tube A by welding, brazing or other means. One of the metal flanges B is provided with a grooved portion C to which 70 abrasive media, such as sandpaper, etc., may be attached. Curved centrifugal weights D are disposed between the flanges B.

75 Referring to Figure 6, a coupling is shown for operatively connecting a plurality of rotary hones, and comprises a tube E having a longitudinal hole 6^b disposed therein, to accommodate the rod 6^a. The tube E is provided with integral segments F, forming openings G therebetween for receiving the extended flanges B of the hones. 80

85 Referring to Figure 8, the groove C in one of the radial flanges is shown as comprising a vertical slot I and an offset wedge-shaped slot J. The abrasive paper H is inserted in the vertical slot I and a wire K is driven endwise into the 90 largest portion of the offset and wedge-shaped slot J.

95 Referring to Figure 9, there is disclosed a modified form of the invention in which the paper securing means comprises a single wedge-shaped slot O and a similarly shaped metal binding P which is compressed on the paper H. In practicing this form of the invention the metal binding P and its attached paper is inserted endwise into the wedge-shaped slot O. 100

105 Referring to Figure 10, there is disclosed a further modification of paper securing means which comprises a round slot L having a restricted opening M. The operation for securing the abrasive paper to this form of groove is similar 110

to that for Figure 8 in that the paper H is inserted into the groove until it assumes a round shape, and the wire K is inserted endwise into the central portion thereof.

5 While we have shown and described several specific embodiments of our invention it will be understood that we do not wish to be limited exactly thereto, since various modifications may be made without departing from the scope of our invention, as defined in the following claims.

We claim:

1. In a honing apparatus for tubular work-pieces, a honing spindle comprising a tubular body, a plurality of radially disposed longitudinal flanges integral with said tubular body, segments disposed entirely between said flanges, and abrasive media associated with said segments and said flanges.

15 2. In a honing apparatus for tubular work-pieces, a honing spindle comprising a tubular

body, a plurality of radially disposed longitudinal flanges integral with said body, centrifugally movable segments disposed between said flanges, abrasive media for said segments and said flanges, and means associated with at least one of said flanges for holding said media.

3. In a honing apparatus for tubular work-pieces, a honing spindle comprising a plurality of tubular bodies, a plurality of radially disposed longitudinal flanges connected to and extending beyond the ends of each of said tubes, segments disposed between said flanges, abrasive media for said segments and said flanges, and a coupling comprising a tube having a plurality of radially disposed segments for operatively connecting the flanges extending beyond the ends of said tubular bodies.

JOSEPH H. GETTIG.

ALLEN D. GETTIG.
